UNITED STATES PATENT OFFICE.

WILLIAM GEIB, OF MERIDEN, CONNECTICUT, ASSIGNOR TO INTERNATIONAL SILVER COMPANY, OF MERIDEN, CONNECTICUT, A CORPORATION OF NEW JERSEY.

DESIGN FOR A BOX OR SIMILAR ARTICLE.

Application filed August 13, 1923. Serial No. 7,000. Term of patent 7 years.

To all whom it may concern:

Be it known that I, WILLIAM GEIB, a citizen of the United States, residing at Meriden, in the county of New Haven and State of Connecticut, have invented a new, original, and ornamental Design for a Box or Similar Article, of which the following is a specification, reference being had to the accompanying drawing, forming a part thereof.

my design, repeat portions of one ornamentation extending around the box being omitted; and

Fig. 2 is a front elevation of the same, repeat portions of two ornamentations extending around the box being omitted.

I claim:

The ornamental design for a box or similar article substantially as shown.

WM. GEIB.
